TRAFFIC SIGNAL

Filed April 26, 1932

Inventor
Edward Lindner
By J. W. Williamson
J.W.

UNITED STATES PATENT OFFICE

EDWARD LINDNER, OF PHILADELPHIA, PENNSYLVANIA

TRAFFIC SIGNAL

Application filed April 26, 1932. Serial No. 607,557.

My invention relates to a new and useful improvement in traffic signals, and has for one of its objects to provide an exceedingly simple and effective device of this description by which a distinctive sound will be given forth, which sound may be a combination of distinctive sounds, such as two or more whistles of different pitch.

A further object of the invention is to put 10 the sounding of the signal under ready control of the traffic officer or other authorized person and enable the signal to be sounded with little or no effort on the part of said authorized person.

15 A still further object of the invention is to provide a power driven blower in which one or more whistles may be inserted so that the rotating of the blower will cause said whistles to be sounded.

20 With these and other ends in view, this invention consists in the details of construction and combination of elements hereinafter set forth and then specifically designated by the claim.

25 In order that those skilled in the art to which this invention appertains may understand how to make and use the same, I will describe its construction in detail, referring by numerals to the accompanying drawing forming a part of this application, in which:—

Fig. 1, is a side elevation of my improved traffic signal.

35 Fig. 2 is a plan view of Fig. 1.
Fig. 3 is an elevation of the signal casing having the face plate removed and being partly in section so as to show the manner of attaching the whistles to said casing.

40 Fig. 4 is a section on the line 4—4 of Fig. 3, looking in the direction of the arrow, showing the motor in elevation and in proper relation to the signal casing.

45 In carrying out my invention as herein embodied, 10 represents the signal casing having a circular space 11 therein in which the fan blades 12 are intended to revolve.

50 13 represents an electric motor of any suitable design and capacity having its power shaft 14 projecting into the space 11 and on this extended shaft is clamped a split hub 15

by means of the bolts 16 and between the sections of this split hub are secured the blades 12 as clearly shown in Fig. 3.

The signal casing is provided with a cover 17 which is secured in place by the bolts 18 intended to be threaded into the holes 19 formed in said casing so that by the removal of this cover easy access may be had to the interior of the casing for the inspection or repair of the fan.

20 represents the base upon which the signal casing and the motor are mounted and may be of such shape or design as to be readily attached to a traffic signal post or other desired object.

25 represents nipples which are formed with the casing 10 and these nipples are of such shape as to readily receive the shanks of the whistles 22 and when said whistles are in place they are securely held against accidental displacement by suitable screws 23 as will be readily understood, and while these whistles may be of any desired type, I have here shown that type of whistle in which a small ball 24 is so housed as to rapidly move back and forth over the air outlet 25 to give a trilling sound.

30 The electric wires 26 lead from the motor to any suitable switch or push button so that when the device is used in connection with a traffic sight signal the changing of such signal 80 may be utilized to start the motor and revolve the blower blades 12, thereby drawing in air through the openings 27 and forcing said air out through the whistles to give the proper audible signal.

35 Or where it is desirable to operate the audible signal independent of a sight signal, the operation of the switch or button for sending a current through the motor may be accomplished by hand.

40 While I have shown two whistles inserted in the casing, there may be any number of openings for the insertion of such whistles and when a number of whistles are so used each may have a different tone quality which when all are sounded in unison will bring about a distinctive composite sound, thus rendering the device especially adapted for use as a riot call or bandit alarm for banks and the like.

By making the whistles removable it enables one whistle to be interchanged with another, thereby providing for giving a different composite sound to the signal so that the signal may be set for any given distinctive sound thus distinguishing one signal from another.

Of course I do not wish to be limited to the exact details of construction as herein shown, as these may be varied within the limits of the appended claim without departing from the spirit of my invention.

Having thus fully described my invention, what I claim as new and useful is:—

15 An audible power signal consisting of a hollow casing having inlet openings formed in the face thereof, a cover for closing the casing, a power shaft projecting into the casing, a split hub adapted to clamp upon the 20 shaft, two fan blades adapted to be secured between the sections of the hub when the latter is clamped upon the shaft, nipples formed with the casing and having outlets therethrough and whistles removably secured 25 in said whistles.

In testimony whereof, I have hereunto affixed my signature.

EDWARD LINDNER.
